UNITED STATES PATENT OFFICE.

GENEVIEVE PFEFFER, OF SAN JOSE, CALIFORNIA.

DESIGN FOR DECORATION OF A FIGURETTE.

57,262.

Specification for Design.

Patented Mar. 8, 1921.

Application filed February 28, 1920. Serial No. 362,125. Term of patent 14 years.

To all whom it may concern:

Be it known that I, GENEVIEVE PFEFFER, a citizen of the United States of America, and a resident of San Jose, California, have invented a new, original, and ornamental Design for Decoration of a Figurette, of which the following is a specification, reference being had to the accompanying drawing, showing, in Figure 1, a side view of the figurette embodying the design, and in Fig. 2 a front view of said figurette.

For the purposes of illustrating this invention I have used the figure of a well known figurette to which, as such, no claim is made in this application apart from the specific design shown.

The new design consists in the application of strips of real fabric lace edging adhering to the figurette as shown at *a*, at

those parts thereof which correspond to the terminal edges of the wearing apparel, namely, at the neck, the arms, the knees, the shoes, and the head covering.

The essence of my invention resides in the general appearance and the unique effect produced by the use of a fabric lace *a* in conjunction with a non-fabric painted garment *b*. It is to be understood that my claim includes all substantial equivalents of my design as shown and described.

I claim:

The ornamental design for decoration of a figurette substantially as shown and described.

In testimony whereof I have hereunto set my hand.

GENEVIEVE PFEFFER.
